UNITED STATES PATENT OFFICE.

RALPH C. SIMMONS, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed December 8, 1919. Serial No. 343,381.

To all whom it may concern:

Be it known that I, RALPH C. SIMMONS, a citizen of the United States, residing at Beverly, in the county of Essex and State 5 of Massachusetts, have invented certain Improvements in Heel-Building Machines, of which the following description, in connection with the accompanying drawings, is a specification, like reference characters on the 10 drawings indicating like parts in the several figures.

This invention relates to shoe machines, and more particularly to heel building machines by which heel lifts formed of leather 15 or other suitable material are assembled to form heels.

Automatic heel building machines have heretofore been proposed but have not met with the commercial and practical success 20 desired by reason of the difficulty encountered in maintaining control of the individual lifts, complication in construction and consequent slowness of operation of the machines, difficulty in pasting and in operating 25 upon the pasted lifts. In a prior application, Serial No. 81,405, filed March 1, 1916, a heel building machine was shown and described which, to a large extent, overcame the previously existing practical difficulties 30 mentioned. In the machine of that application a series of heel lifts is taken from a series of stacks and simultaneously placed upon lift supports arranged in the plane of the bottom of the stack, and assembling 35 means thereafter moves the individual lifts from the supports onto other partially formed heel piles by movement of the assembling means the distance of separation of the stacks after each supply of heel lifts. 40 This machine has given satisfactory practical results and the present invention is a further development of this general type of machine.

As in the machine of the prior application, the present invention provides for removing a series of heel lifts from a corresponding series of stacks and simultaneously delivering the lifts to a support, which, however, is not in the plane of the bottoms 45 of the stacks or magazines but preferably 50 of the stacks or magazines but preferably a sufficient distance below such plane that

the heel lifts may be delivered directly upon incomplete piles of heel lifts previously formed. An important feature of the invention, therefore, consists of a heel lift support normally in fixed relation to the stacks, below the bottom, and at one side thereof, and to which a series of heel lifts is delivered simultaneously.

In the practical embodiment of this feature, magazines are provided to hold a series of stacks of heel lifts, and the lift support is arranged to extend past and adjacent to the magazines below the plane of their bottoms. The heel lifts are moved from the 65 magazines, and when they are to be supplied with paste or an adhesive, they are passed over pasting means, and then simultaneously delivered to the lift support, all except the first lift of the series being deposited upon a partially formed heel pile.

It is desirable that the lifts in the partially formed heel piles be retained in substantially their co-related superposed positions as they are moved intermittently along the support notwithstanding the fact that in practice, at least, it is usual to gradually diminish the size of the lifts upwardly of the pile. Another important feature of the invention therefore consists 75 of guides which converge upwardly from the lift support and gradually increase in height towards the point of delivery of the completed pile of heel lifts.

The heel lifts are removed from the magazines or stacks by pushers to which the lifts are liable to adhere on account of the film of paste that lodges between the pushers and lifts. In this event the lifts, or some of them, are liable to follow the pushers as 80 the latter retreat and fail to be delivered, and imperfect heel piles are liable to be formed. Another important feature of the invention consists of means to engage the trailing edge of the lifts when they reach 85 the point of delivery and positively prevent the lifts following the pushers as they retreat. This feature of the invention may be carried into practical effect by means of lifters or stops which drop behind the 90 lifts when they reach delivery position.

It is important to stop the machine should

one or more heel lifts fail to be delivered, because otherwise the machine may continue to build imperfect heel piles. To this end the present invention provides, and an important feature of the invention consists of, a series of lifters or fingers which are moved by the advancing heel lifts as they approach delivery position, and failure to move or lift any one of them, which signifies that no heel lift is being delivered at this point, is utilized to stop the machine.

The heel lifts which are delivered in a row to the depressed heel lift support, are advanced intermittently along the support by a lift assembling means or conveyor, which is given a movement of advance after each delivery of heel lifts. Should the intermittent advancing movement of the assembling means or conveyor meet with an undue obstruction, breakage is liable to occur in the absence of means to stop the machine under such conditions. Another important feature of the invention, therefore, consists in improved means for stopping the machine when the assembling means or conveyor meets an unusual or undue obstruction which is liable to cause breakage of parts.

Where quick drying paste is applied to heel lifts as they are advanced to delivery position, it is desirable to maintain the paste in sufficiently liquid form and prevent, as far as possible, accumulation of the paste upon the paste rolls. The desired liquid condition of the paste is maintained by submitting the paste to the action of heat, and to prevent an accumulation of paste upon the paste rolls, especially when the machine is stopped, the illustrated embodiment of the invention is provided with means for continuously rotating the paste rolls, and maintaining such rotative action of the paste rolls even while the machine as a whole is at rest. In the present instance, the paste rolls, or paste roll, may be driven continuously from the driving pulley of the machine, a clutch being interposed between the driving pulley and machine operating parts to enable the machine itself to be stopped while the paste roll or rolls continue in operation.

It is desirable under some circumstances to apply to the surface of the heel lift a film of paste or adhesive which varies in thickness over different portions of the lift, and also it is desirable at times to apply a different thickness of film to the different lifts of the series. An important feature of the invention in this respect consists in a series of scrapers arranged adjacent to the path of movement of the lifts and independently adjustable towards and from and angularly with relation to the paste rolls or roll. In practically carrying out this fea-

ture of the invention, the pasting means consists preferably of a series of paste cylinders or rolls mounted on the same shaft and each positioned adjacent the path of movement of the heel lifts from the magazines to the depressed heel lift support. With this construction, a separate scraper is advantageously employed with each of the paste rolls, and each of the scrapers is independently adjustable relative to its cooperating roll.

Where the heel piles are to be formed of wedge-shaped lifts, it is important that the lowermost lift of the series be presented in a plane substantially in the plane of the pusher or feeding means which acts to move it from the magazine. Where wedge-shaped lifts are piled in a substantially vertical column from top to bottom of the stack, the weight of the superposed lifts upon the bottom lift tends to tilt the thin or breast edge of the lift upwardly and, consequently, interferes with the free moving of the lift from the stack by the advancing feeding means or pusher. An important feature of the invention, therefore, consists in means for causing the lowermost lift of the series to be moved rearwardly or towards the thickened wedge portion of the lift as it approaches feeding position. This feature of the invention may be variously contrived, but in the present instance is embodied in guiding means which, as the wedge-shaped lifts approach the position of feed, are moved rearwardly to transfer the weight of superposed lifts towards the front or breast edge of the lowermost lift.

The above features of the invention and other novel combinations of parts will be hereinafter described in connection with the accompanying drawings which illustrate one good, practical form of the invention.

In the drawings:

Fig. 1 is a view in front elevation of an automatic heel building machine embodying the present invention, some of the parts being omitted and others broken away for clearness of illustration;

Fig. 2 is an end elevation of the machine, some of the parts being broken away to show others beyond;

Fig. 3 is a plan view;

Fig. 4 is a cross section on the line 4—4 of Fig. 3, the parts being shown on an enlarged scale;

Fig. 5 is a detached enlarged plan view showing one of the paste rolls and its cooperating scraper and the means for relatively adjusting the two;

Fig. 6 is an enlarged sectional view showing more particularly the parts in front of the line of magazines;

Figs. 7, 8 and 9 are cross sectional views of the heel lift support and upwardly ex-

tending side guides at different points longitudinally of the machine;

Fig. 10 is a detail showing the finger or lifter and its actuation by a heel lift as it passes thereunder to the lift support;

Fig. 11 is a view similar to Fig. 10 showing the finger or lifter in its dropped or stopping position to prevent the heel lift following the pusher as the latter retracts.

Fig. 12 is a detached detail of certain portions of the stopping mechanism;

Fig. 13 is a perspective view showing the general organization of the stopping and the clutch controlling mechanism;

Fig. 14 is a detail side elevation on an enlarged scale, showing the mechanism for stopping movement of the heel assembling mechanism or conveyor when the latter meets with undue resistance to movement;

Fig. 15 is a sectional detail of certain features thereof;

Fig. 16 is a plan view on an enlarged scale showing a magazine for containing wedge-shaped heel lifts;

Fig. 17 is a section on the line 17—17 of Fig. 16;

Fig. 18 is an enlarged diagrammatic view showing, on an enlarged scale, the arrangement assumed by the lowermost and superposed wedge-shaped heel lifts, when the lowermost lift is in lift feeding position;

Fig. 19 is a detail front view of the key-hole slot formed in the stem for supporting the wedge-shaped lifts.

The main frame of the machine may be suitably constructed to sustain the various elements of the machine, and in the present instance comprises the end members 10 between which extend the tie beams or braces

11. Connected to the main frame by the joints or hinges 13, is an auxiliary frame 14. The auxiliary frame 14 consists essentially of a plate or casting and a series of parallel partitions 15; Figs. 1 and 3, extending forwardly from the rear plate or casting 16 of the auxiliary frame to form passage ways 17, in which operate the lift feeding means or pushers, as will more fully appear.

In the passage-ways 17 between the partitions 15 is mounted a series of heel lift magazines, Figs. 1 and 2, in which are supported stacks of heel lifts. When the piles of lifts to be formed are to be built from heel lifts of uniform thickness throughout, the magazine for supporting the stacks of heel lifts may be substantially as fully shown and described in the prior application, and substantially as indicated in Figs. 1, 2 and 6, wherein the magazines for this character of lifts consist of the opposed walls 18 and 19 in which the heel lifts 20 may be stacked and by which they may be guided to the delivery or feed point at the bottom portion of the magazines. To accommodate the

magazines to lifts of different sizes, the walls 65 18 and 19 are preferably adjustable relatively, as indicated in Fig. 2, by the adjusting bolts 21 passing through suitable slots in the portion 22 rising from the auxiliary frame. 70

The lowermost heel lifts in the series of magazines thus provided lie upon a rest 23 in the path of the feeding means or pushers, to be described. The rest 23 preferably consists of a grid either made up of a plurality 75 of bars, as pointed out in the prior application, or formed as a grooved table, the latter being the form of rest herein illustrated. The grooved table extends from near the rear to a point near the front of the passage-ways 17 between the partitions 15, the sharpened edges of the grooved construction acting to resist angular movement of the lifts as they slide along the grid towards delivery position to the depressed lift support, 80 as will later appear, and also acting in a measure to prevent the accumulation of paste which is applied to the surface of the heel lifts as they are moved from the magazines toward delivering position. 85

Extending longitudinally of the machine in front of the line of magazines, is a paste roll shaft 24 which is provided with a series of paste rolls 25, one projecting into each of the passage-ways 17 in front of each of the 90 magazines, the purpose being to provide means for delivering paste to the surface of the series of heel lifts as they are moved from the magazines, towards delivery position, to the depressed heel lift support. In 95 the present instance of the invention the table or rest 23 formed as hereinbefore described, is interrupted at the point where the paste rolls 25 are located to permit the surface of the paste rolls to project upwardly 100 into the line of feed of the lifts. 105

The paste rolls 25 extend into the paste trough 26 which contains a sufficient quantity of paste to supply the rolls. The trough 26 may be conveniently supported either at its end or upon longitudinally extending beam members 27 and 28, Figs. 4 and 6, which, together, form a chamber 29 for maintaining the paste or adhesive in sufficiently liquid form for ready application to 110 the heel lifts. 115

Where the heel lifts are to be assembled in piles soon after the application of paste thereto, it is desirable to employ a quick drying paste or adhesive and in order to 120 maintain such quick drying paste or adhesive in proper liquid form, its temperature is kept sufficiently high by some form of heating means. In the present instance of the invention the chamber 29 formed of the members 27 and 28 has extending longitudinally thereof the heating pipes 30, Figs. 4 and 6, which may be connected to a suitable 125

source of heat supply as, for instance, a steam generator. The paste trough 26 may be conveniently supplied with paste or adhesive from a storage tank 31, Fig. 1, which connects by means of a pipe 32 to the paste trough 26, a valve 33 being preferably provided between the supply tank 31 and the paste trough to regulate the flow of the paste to the latter. By providing a valve 34 at the top of the tank, as indicated in Fig. 1, a very full and complete control of the flow of paste to the paste trough may be exercised. By opening the valve 34 and the valve 33 a quick flow of paste into the trough may be accomplished, whereas by closing the valve 34 and opening the valve 33 a slow delivery is maintained.

The film of paste that is applied to the surface of the heel lifts is regulated by 20 scrapers which act in cooperation with the several paste rolls or cylinders 25, and inasmuch as it may sometimes be desirable to apply more paste to some of the lifts than others, or to apply paste more copiously to 25 one part of the heel lift than another, the scrapers are mounted independently and adjustably relative to the cooperating paste rolls 25. In the present instance of the invention the longitudinally extending member 27 has rising therefrom at intervals, the lugs 36, Figs. 5 and 6, in which is pivotally mounted at 37 a scraper. Since all 30 the scrapers are alike, a description of one will suffice for all. The scraper 38 has a scraping portion 39 and a tail portion 40 extending into the paste trough 26. To adjust the scraping edge portion 39 of the scraper towards and from the paste roll, the scraper has a backwardly extending 40 flange 41 through which extend the adjusting screws 42, one being threaded into and the other resting upon the upper surface of the horizontal portion of the lugs 36. By loosening one screw and tightening the other, it will readily appear that the particular scraper may be moved into closer or 45 more remote relation to its paste roll and that each of the scrapers is adjustable independently of all the others.

50 The lugs 36 in which the scraper is mounted have a forwardly extending flange portion 43 provided with slots 44 through which pass the set screws 45. By manipulating the set screws 45, the scraper 38 may be 55 adjusted angularly relative to its cooperating paste roll 25, as indicated in Fig. 5. The different thickness of the film of paste that may be desired to be applied to the different portions of the lift, can readily be 60 controlled by the adjustments described.

The heel lift support 46, Figs. 4 and 6, extends past the magazines longitudinally of the machine and on a plane below the bottoms of the magazines, the general construction being such that as the heel lifts are

65 moved from the magazines, in a manner to be hereinafter described, they are delivered to the depressed heel lift support or directly onto other partially formed heel lift piles, under conditions to be more fully explained. 70

The heel lift support is provided with side guiding members 47 and 48 which are adjustable towards and from each other by means of the adjusting or holding bolts 49 and 50, Fig. 6. The present invention contemplates that a series of lifts shall be delivered to the heel lift support simultaneously and that the heel lifts then on the support shall be given an intermittent advancing movement after each delivery of a 80 row of lifts, with the result that every lift of the row delivered, except the first one, will be dropped upon a partially formed pile of heel lifts and the end pile of lifts will constitute a complete heel pile. Thus the piles 85 of lifts, as they advance towards the delivery end of the lift support and guideway increase in height, and to provide for the proper guidance of the pile of lifts as it 90 gradually grows, the side members 48 and 47 are gradually increased in height from one end of the machine to the other, as illustrated by the cross sections in Figs. 7, 8 and 9, wherein it will be noted that the side 95 guides 47 and 48 are comparatively low in Fig. 7 which is a cross section near the first magazine of the series, but are higher in Fig. 8, which is a cross section at an intermediate point of the side guides and heel lift support, and that in Fig. 9 the side guides 47 and 48 are equal to or greater than the height of a completed heel pile. In 100 order to impart intermittent movement to the heel lifts on the heel lift support 46, which extends uninterruptedly past the series of magazines, an assembling mechanism or conveyor is provided which is given an intermittent or step-by-step movement 105 after every delivery of a series of heel lifts to the support.

The paste rolls 25 which act upon the series of lifts as they are moved from the magazine for delivery to the heel lift support, serve to assist the feeding means or pushers, to be described, in the feeding movement of the heel lifts, but to insure that they are pressed with sufficient firmness into contact with the paste rolls to receive the film of paste, the present invention provides means associated with each of the magazines for holding the heel lift of each of the magazines against the paste roll as it is advanced by the feeding means. In the present instance of the invention, Fig. 6, the bracket 51 has adjustably secured thereto a forwardly extending plate 52, the rear end or magazine end of which may form a step 53 to prevent the lift resting upon the bottom lift from following it or being moved with 110

it as the bottommost lift is pushed or moved from the magazine. Pivotally mounted on the plate 52 at 54 is the heel lift depressing means which consists of a plate 55, preferably trough-shaped, to enclose between its upturned side flanges the plate 52. A spring 56 normally acts upon the magazine end of the plate 55 to depress that end and an adjusting screw or stop 57 serves to limit the action of the spring. In order to guide the bottommost lift under the plate 55 and into intimate contact with the paste roll, the plate 55 has extending rearwardly therefrom towards the magazine, the curved resilient fingers 58, Fig. 6, the construction being such that as the lowermost lift of the stack is moved towards the heel lift support, it encounters the resilient and curved fingers 58 and it is guided by them downwardly onto the cooperating paste roll 25 and held against the paste roll by the plate 55 as the heel lift moves to delivery position. The front end portion 59 of the plate 55 may be slightly downturned to hold the heel lift firmly upon the rest 23 as it is moved over the top of the side guide 47 and under a lifter or finger, to be presently described. The bracket 51 is adjustably mounted relative to the magazine by means of the bolts 60 and 61, which pass through slots in the bracket, as indicated in Fig. 6.

It is appropriate at this time to describe the heel lift feeding means and cooperating parts. Mounted in suitable bearings in the machine frame, is the main or drive shaft 62, Figs. 2 and 3, having splined thereon one member of a clutch 63. The clutch 63 may be of any usual type well known in the art. Loosely mounted upon the shaft 62 is the pulley 64 which may be continuously driven from an appropriate source of power such, for instance, as a belt connection with a line shaft. The other member of the clutch is connected to or formed as part of the pulley 64, the construction being such that when the clutch members are disengaged, the drive shaft 62 will remain at rest while the pulley 64 will continue to rotate, but when the clutch members are thrown into engagement, as will later appear, the shaft 62 will rotate in unison with the pulley 64.

Hereinbefore mention has been made of the fact that a quick drying paste is preferably employed and in such event that the paste rolls or roll should be continuously driven, even though the machine itself may be at rest. This continuous rotation of the paste roll is accomplished in the present instance of the invention by a sprocket chain 65, Fig. 2, connected to a sprocket 66 on the paste roll shaft 24, and another sprocket 67 on the shaft 68 supported by a suitable bracket 69, as best indicated in Figs. 2 and 3. The shaft 68 has secured thereto a gear 70 which is operatively engaged with a gear

71 connected to and operating with the continuously driven pulley 64, the construction being such that as long as the pulley 64 continues to rotate, the paste roll shaft 24 will continue in operation.

Mounted for rotative movement in the end frame members 10 of the machine and appropriately supported is the cam shaft 72, Figs. 3 and 4, which is driven from the main shaft 62 through a train of gearing 73 and 74, the gear 73 being secured to the shaft 62, and the gear 74 to the cam shaft 72.

The cam shaft 72 carries near its end opposite the gear 74, a cam member 75, and in the faces of the gear 74 and the cam member 75 are formed similar cam grooves 76, as indicated in Figs. 2 and 4. The cam grooves 76 in the gear 74 and cam member 75, engage respectively the rolls 77 connected respectively to the arms 78, one adjacent each end of the machine frame, which arms are pivoted at their lower ends at 79 for rocking movement under the operative influence of the cam grooves 76 and the rolls 77. The rocking arms 78 are connected at their upper ends by links 80 to a slide or pusher actuating means 81, which, in the present instance of the invention, is mounted for reciprocating movement towards and from the front of the machine, in the guideways 82, Fig. 4, formed on the machine frame.

The slide 81 has connected thereto a number of pushers for pushing the lowermost heel lifts from the several stacks of heels and delivering them over the guideway 47 to the heel lift support below, or to other partially formed heel piles. The connection between the pushers and the slide 81 may be variously contrived, but in the present instance the slide 81 is provided with a series of pins 83 which are adapted to register with complementary holes formed in pushers 84, Figs. 3 and 4. The pushers 84 are preferably formed as plates, for convenience of manufacture and effectiveness in operation, and may be readily connected to or detached from the slide 81 by simply disengaging the pushers from the pins 83.

When the machine is in operation, the slide 81 is reciprocated in its guides 82 and actuates the series of pushers 84 which are connected thereto, and these, in turn, move a series of lifts equal to the number that are to appear in any complete heel pile, and deliver them to the depressed heel lift support or other partially formed piles. Manifestly, should any pusher fail to deliver a heel lift, the corresponding heel pile will be imperfect and a continuance of non-delivery of a heel lift is apt to produce quantities of heel piles of unsatisfactory heights. The present invention, therefore, aims to provide means for stopping the machine in case of the non-delivery of any one of the heel lifts of the series. Extending between the

end members of the auxiliary frame 14, is the longitudinal bar or member 85, Fig. 6. Secured to the bar 85 is a series of supports or brackets 86, one positioned opposite each magazine, and pivotally mounted upon the lower end portion of the brackets 86 is a series of lifters or fingers which constitute a part of the stopping mechanism, and as these are of similar construction, a description of one will be sufficient for all. The lifter or finger 87, Fig. 6, is pivotally mounted upon a pin 88 carried by the bracket 86. The lifter or finger 87 is provided with a slot 89, whereby the finger or lifter may be adjusted relative to its pivotal support. The rear edge portion of the lifter 87 is inclined, as at 90, and its front edge portion at 91 rests upon the top of the guide 47, the construction being such that when a heel lift is moved from any one of the magazines for delivery to the heel lift support, it passes under its associated lifter 87, as indicated in Fig. 10, thereby raising the lifter and maintaining it in raised position until the heel lift 20 has passed.

Mounted upon the bar 85 for rising and falling movement, is a slide or rod 92, one being associated with each of the lifters 87 and preferably guided for vertical movement in the guides 93. Pivotally mounted upon the bracket 86 at 94 is a lever 95 through which is passed an adjusting screw 96, the lower end portion 97 of which rests upon the top of the slide or rod 92, it being understood that there is one of the levers 95 associated with each of the lifters. Secured to each of the levers 95 is a stop arm 98, the down-turned end 99 of which is adapted to project into the path of movement of the feeler member 100 which is mounted upon the arms 101 secured to the rock shaft 102. The arms 101, of which there may be two or more, are indicated in Fig. 1, one near either end of the series of magazines and the feeler 100 is supported by the said arms. These arms may be secured to the rock shaft 102 in any appropriate manner, but as illustrated in Fig. 6, they are secured in place by means of a clamping bolt 103 and a split collar 104 embracing the rock shaft. From the construction described, it will be apparent that should the feeler 100 meet with an obstruction in its oscillating movement by one of the stop fingers 99 being in its lowered position, as indicated in Fig. 6, a position which indicates the nonpresence of a heel lift, the feeler member will be stopped, and this condition is utilized in stopping the machine, as will presently appear.

Rocking movement is imparted to the rock shaft 102 in one direction, in the present instance of the invention, through means actuated from the slide 81, as indicated more clearly in Fig. 13. The slide 81, Fig. 13, is

provided with an inclined lug 105 which, as the slide moves frontwardly, rides under a roller 106 carried by a swinging frame 107 pivotally mounted at 108 on the bell crank lever 109 which is itself supported for rocking movement by a lug 110 rising from the machine frame 10. The bell crank lever 109 has connected with it at 111 the rod 112 which is pivotally connected at 113 to the arm 114, which is secured to the rock shaft 102, the construction being such that on rocking movement being imparted to the bell crank 109, movement will be transmitted to the rock shaft 102 to the right, Fig. 13, and, perforce, to the feeler member 100. As the slide 81 moves frontwardly, the inclined surface of the lug 105 passes under the roller 106 and rocks the bell crank 109, and then passes frontwardly of the roller 106. On its backward movement, the lug 105 again meets the roller 106 and turns the swinging frame 107 on its pivot 108 to permit the lug to pass, that is, the swinging frame 107 may freely swing clockwise, or to the left, Fig. 13, but not contra-clockwise, or to the right. To move the rock shaft 102 in the opposite direction from that imparted by the bell crank 109, an arm 115 depending from the rock shaft 102, is under the influence of a spring 116 normally tending to yieldingly turn the rock shaft in the opposite direction and move the feeler to the left, Fig. 13.

A rod 117 is supported for sliding movement on the frame of the machine, Figs. 2 and 13, in suitable lugs 118. A spring 119 interposed between the head 120 of the rod and one of the bearings 118, normally holds the rod 117 projected to the right, Fig. 2, with the limiting stop 121 against the other bearing 118. Pivotally mounted upon the rod 117 at 122, Figs. 2 and 13, is a gravity catch 123, the shouldered end portion 124 of which is normally positioned below the path of movement of the lug 125 carried by the slide 81. The catch 123 may be weighted, as at 126, to normally maintain the shouldered portion 124 of the catch in its depressed position. The catch 123 has a depending tail piece 127 in which is tapped an adjusting screw 128 the head of which is in the path of movement of a catch operating rod 129, the front end portion of which is connected at 130 to the depending arm 115 secured to the rock shaft 102.

From the construction thus far described it will be apparent that upon frontward movement of the slide 81, the rock shaft 102 will be turned or rocked and the feeler 100 will be moved to the right to carry the feeler frontwardly away from the stop fingers 99, and at the same time the shouldered portion 124 of the catch 123 will be lifted. When the lug 105 on the slide 81 passes the roll

106 on the bell crank 109, the spring 116 further asserts itself and rocks the shaft 102 in the opposite direction and, perforce, moves the feeler to the left, Fig. 13. If, at the 5 time, one of the stop fingers 99 is in the path of movement of the feeler 100 and its movement to its dotted line position, indicated in Figs. 4 and 6, is obstructed, the shoulder 124 of the catch 123 will remain 10 in the path of the lug 125 of the slide 81 and be engaged thereby as the slide moves rearwardly. As hereinbefore stated, the lowered position of any one of the stops 99 indicates the absence of a heel lift and, 15 consequently, imperfect delivery of the required number of lifts to the lift support. Consequently, when the catch 123 is engaged by the lug 125 of the slide, as the latter moves rearwardly, it moves the rod 117 along with 20 it and advantage is taken of this movement to effect stopping of the machine.

The splined clutch member carried by the driving shaft 62 is under control of a yoke 131 having a hub portion 132, Fig. 13, by 25 which it is mounted for rocking movement on the machine frame. The yoke 131 is normally under the influence of a spring 133 acting to disengage the clutch members. A stop rod 134, Fig. 13, is mounted 30 in suitable bearings 135, Fig. 2, and carries at its rear end portion a clutch actuating member 136, Fig. 13. Extending upwardly from the stop rod 134 is a hand lever 137 by means of which the stop rod 134 may be 35 rocked to move the yoke 131 against the tension of its spring 133 and engage the clutch members. The lever 137 is connected at its upper end at 138 to a hand piece 139 which extends longitudinally in front of the 40 machine, and is pivotally connected at its upper end at 140 to a lever 141 pivoted at 142, the construction being such that by movement of the hand piece 139 by the attendant at any point in front of the 45 machine, the stop rod 134 may be rocked to start the machine or, as will later appear, to stop it.

Mounted in suitable bearings 144, is the latch rod 145, Fig. 13. A spring 146 interposed between the bearing 144 and the collar 147 on the latch rod, normally tends to depress the latch rod to carry its lower end 148 into the path of movement of the yoke 131 when the latter is moved to engage the 50 clutch members and to maintain the clutch members in operative relation against the tension of the yoke actuating spring 133.

The latch rod 145 at its upper end portion carries a transversely extending pin 149, Fig. 12, which straddles the upper bifurcated end of the rod. Secured to the rod 117 is the trip finger 150, Fig. 12, having an upwardly inclined surface 151 which, when the rod 117 is moved to the left, Fig. 55

13, by engagement of the gravity catch with 65 the lug 125 of the slide, is adapted to be moved under the pin 149 and lift the latch rod, thereby carrying its lower end 148 from the path of movement of the yoke 131 to permit the spring 133 to disengage the 70 clutch members and, as hereinbefore noted, thereby effect stoppage of the machine.

The stop rod 134 has secured thereto an upwardly extending member 152, Fig. 13, the upper end portion of which is provided 75 with a cam surface 153 adapted to engage a roll 154 on the latch rod 145, the construction being such that when the machine is stopped by failure to feed one of the heel lifts, as hereinbefore described, the stop rod 134 will be rotated or oscillated through the effort exerted upon the member 136 by the yoke, as it moves in response to its actuating spring 133, and the latch rod will be maintained in its upper or inoperative position 80 relative to the yoke. When the machine is to be started by hand, the stop rod 134 is rocked to engage the clutch members and coincidentally therewith to remove the cam 85 153 from beneath the roll 154 and thereby permit the lower end of the latch rod to lock the yoke with the clutch members in operative relation and, conversely, when the rod 134 is rocked through the hand lever 137 to stop the machine by hand, the cam member 90 153 again rides under the roll 154 of the latch rod and removes the end 148 of the latch rod from the path of movement of the yoke. The stop rod 145 may be provided 95 with a stop 155, Fig. 13, for limiting its 100 downward movement in response to its spring 146.

When the machine has been stopped by failure to feed one of the heel lifts to the lift support, the attendant will remedy the 105 defect in the feed and remove the stop 99 from the path of the feeler, whereupon the gravity catch 123 will drop and the parts resume their position, as indicated in Fig. 13.

The assembling mechanism or conveyor 110 for intermittently moving the row of heel lifts along the uninterrupted lift support, comprises a chain or conveyor 156, Fig. 1, which is provided with a series of fingers 115 157 suitably spaced apart to accommodate between adjacent fingers the heel lifts which are delivered to the lift support.

Mounted at opposite ends of the machine 120 frame are the sprocket wheels 159 over which the chain or conveyor 156 passes and by which it is given its directional movement. The lift advancing fingers 157 extend outwardly from the chain or conveyor 156 and through a central opening 160 125 formed longitudinally of the lift support, Figs. 4, 6, 7, 8 and 9, suitable runners or supports 161 being provided, as indicated

in Fig. 4, to properly maintain the upper run of the chain with the fingers 157 in proper cooperative relation with the lift support and extending through the opening 160 thereof.

The conveyor or chain 156 is given a step-by-step or intermittent movement for each feed movement of the series of heel lifts, and this may be effected in any suitable manner. Inasmuch, however, as the fingers 157 which effect the advance of the heel lifts along the heel lift support, are substantially non-yielding, means are provided to stop the machine in case of undue obstruction to any of the intermittent movements of the conveyor or chain. In the present instance of the invention, the shaft 162, Figs. 1 and 14, has loosely mounted thereon the rocker 163 carrying a pawl 164, the end of which is adapted to engage with a series of teeth formed on a ratchet wheel 165 secured to the sprockets 159 at that end of the machine. The rocker 163 is given its rocking movement by means of a rod 166 pivoted at 167 to the rocker and having a turn-buckle 168 for purposes of adjustment. The rod 166 passes through an aperture in a stud 169 loosely mounted in the upper end of an actuating arm 170 secured to the rock shaft 171, Figs. 3 and 4. A heavy compression spring 172 surrounds the end portion of the rod 166 and bears at one end against a washer 173 supported by a nut 174 threaded upon the rod 166, and at the other end against a collar 175 which abuts or rests against the stud 169 and through which the rod 166 passes loosely. A pin 176 passing through the rod 166 abuts or rests against the opposite side of the stud 169, thereby positively limiting relative movement between the rod and the arm 170 in one direction, while permitting such relative movement in the opposite direction against the tension of the spring 172. The spring 172 is sufficiently stiff to prevent it from yielding in the normal operation of the machine, and its function, as a part of the means for automatically stopping the machine in the event of undue obstruction to the movement of the conveyor chain, will more fully hereinafter appear.

The rock shaft 171 carries an arm 177, Figs. 3 and 4, provided with a cam roll 178 which operates in a cam groove 179 formed in the periphery of the cam 75 which, as hereinbefore described, is secured to the cam shaft 72. The cam 179 is formed to impart a complete to and fro oscillatory movement to the rock shaft 171 and, consequently, to the arm 170 for each revolution of the cam shaft 72 and, therefore, for each reciprocation of the pushers 84. This oscillation of the arm 170 causes the ratchet 164 and the sprockets actuated thereby, to be advanced through the angle of distance between two

adjacent teeth of the ratchet. The teeth of the ratchet are so spaced that actuation of one tooth will move the lift assembling fingers or conveyor through a space equal to that between corresponding points of adjacent lift magazines, and the mechanism is so timed that the fingers stop in their intermittent movement between the magazines thereby permitting the pushers which are advanced at this time in the cycle of the machine operation, to deposit the row of lifts removed from the magazines upon the lift support 46.

In order to stop the machine upon undue obstruction to the movement of the assembling mechanism or conveyor, the rod 166 is provided with a notch 180, Fig. 15, having a beveled side portion and engaged by a catch 181 having a correspondingly beveled portion 182. In the present instance, the catch 181 is formed on a plunger 183 mounted in a recess in the upper end of the arm 170. The catch 181 is normally held in engagement with the notch 180 on the rod 166 by means of a spring 184, Fig. 15, interposed between a collar 185 at the lower end of the plunger and a cap 186 covering the plunger recess, as indicated in Fig. 15. The spring 184 is of sufficient tension to normally maintain the latch 181 in engagement with the recess 180 in the rod 166, but should the rod 166 meet with undue resistance as the arm 170 moves to the left to thereby advance the assembling mechanism or conveyor, the rod 166 may remain stationary while the arm 170 moves to the left, thereby lifting the latch and, perforce, the plunger in the end of the arm 170.

A toothed segment 187, Fig. 15, is secured to the rocker arm 141 which, as hereinbefore described, is connected to the stop rod 134. The upper end of the plunger 183 is provided with a tooth 188 which, when the plunger is moved outwardly, due to obstruction to the movement of the rod 166 to the left, Fig. 15, engages the toothed segment 187 and, perforce, causes movement of the rocker 141 to the left, Fig. 14, thereby rocking the stop rod 134 and stopping the machine. Thus, should the assembling means meet with any undue or unusual resistance to its intermittent movements, the mechanism is such that the machine may be automatically stopped without danger of breakage of parts.

Where, as in the present instance of the invention, the heel lifts are supplied with paste as they are moved from the magazines to the lift support, the lifts are liable to stick to the pushers as the latter retract, and the invention contemplates means for overcoming this defective action. In the present instance, the lifters or detectors are utilized as a means for preventing the retracting movement of the heel lifts

with the pushers. To this end the pushers are each provided with a slot 189, Figs. 10 and 11, extending from the pushing or leading edge of the pushers inwardly or longitudinally of the pushers, into which the lower end portions 91 of the lifters may drop when, as indicated in Fig. 10, the lifters have been moved to their delivering position. On retraction of the pushers the lifters engage the edge of the lifts, should any stick to the pushers, and detach them from the pushers as the latter move back, thus insuring the delivery of an entire row of lifts notwithstanding any adhesion between the heel lifts and the pushers.

Inasmuch as different sizes of heel lifts may be treated in the machine and corresponding adjustments of the side guides 47 and 48 are provided for that purpose, as hereinbefore indicated, the lifters 87 are similarly provided each with a slot 89 permitting adjustment of the lifters to accommodate heel lifts of different sizes.

Inasmuch as the lowermost heel lift is to be removed from the several stacks and delivered to the heel lift support, it is important that the lowermost lift shall lie flat and in proper feeding position on the rest in front of the feeding means or pusher. Where the heel piles are to be formed of wedge-shaped heel lifts, however, the weight of the superposed lifts is liable to upwardly tilt the thin edge of the lowermost lift. Should this occur the lowermost lift will not be in proper position to be removed from the magazine because the upwardly tilted thin or breast edge will project above the lower adjacent edge of the magazine and obstruct the feeding movement and the pusher will likewise fail to properly engage the lift. The present invention therefore provides means for insuring proper presentation of the lowermost lift of a stack of wedge-shaped lifts to the pusher or feeding device. This is preferably accomplished by distributing the weight of the superposed heel lifts frontwardly or towards the thin breast edge of the lowermost lift when it is in feeding position by relative movement of the lowermost lift in a rearward direction as it passes to feeding position, so that the weight of the superposed lifts tends to depress the thin or breast edge of the lowermost lift and hold the lift flat upon the heel lift rest. A good form of means to this end is best shown by Figs. 16 to 19 inclusive, wherein the grid 23 constitutes the rest upon which the lowermost lift is held when in feeding position.

Rising from the rest or grid 23 is the heel breast guiding wall 190 of the magazine. This may be formed of a plate adjustable relative to the grid or support by the adjusting screw 191. At the lower or discharge end the magazine is provided with

the guides 192 which incline towards the rear of the heel lifts as the guides approach the feeding position for the lowermost heel lift and act upon the thin or breast edge of the wedge-shaped lifts to direct the lowermost heel lift rearwardly. At its upper portion the guiding wall 190 is provided with a supporting pin 193 which may be held in place by a set screw 194. The pin 193 is provided with a head 195 and a collar 197 between which is the shank 196 which is adapted to support a stem 198 on which the wedge-shaped lifts are assembled. The stem 198 is non-circular in cross section and the wedge-shaped heel lifts 200 are provided so with correspondingly shaped openings 199 through which the stem 198 passes. The lower end 201 of the stem 198 is turned or inclined towards the rear of the heel lifts 200, as indicated in Fig. 17 and in conjunction with the inclined guides 192 insures movement of the lowermost heel lift in a direction rearwardly or towards the thicker portion of the lift as it approaches feeding position. The effect of this is to transfer the weight of the superposed lifts frontwardly of the rear or thicker portion of the lowermost heel lift and cause the lowermost wedge-shaped lift to lie flat upon the rest 23. This is best indicated in the graphic representation in Fig. 18, wherein the weight of the superposed wedge-shaped lifts or the gravity pull is represented by the dotted lines a, a which pass through the lowermost lift frontward of its rear or thick edge and press the thin or breast edge downwardly onto the rest beneath.

The wedge-shaped heel lifts are preferably strung upon the stem 198 before the lifts are placed in the heel building machine; and to provide for ready application of the stem 198 with its stack of lifts, the stem has formed therein the key hole opening 203, the larger portion of which will readily slip over the head 195 of the supporting pin whereupon the stem and stack of wedge-shaped lifts may be lowered to cause the shank 196 of the supporting pin to ride into the narrower portion of the key hole slot 203 and lock the stem and stack of heel lifts in the magazine.

Adjacent to the delivery portion of the magazine means may be provided for insuring correct movement of the lowermost lift to feeding position after it leaves the stem. This is effected by the breast inclines 192 hereinbefore described and the guides 202 which may bear upon the contour or curved rear portion of the heel lifts as they successively move to feeding position. To insure that the wedge-shaped heel lifts may not be laterally displaced or be turned in the plane of the lifts as they approach feeding position and particularly after they leave the stem 198, side guides 204 may be advan-

geously employed, one at each side of the inclines 192, Fig. 16. Thus as the wedge-shaped lift approaches feeding position it is moved rearwardly thereby transferring the weight of superposed lift frontwardly upon itself and towards the thin breast edge, and as the lift passes from control of the stem, its proper position relative to the stack and the feeding means is maintained by the edge guides.

As the heel piles are formed and successively completed the lifts of the pile are passed by a series of alining fingers to rectify any improperly placed lift and insure a correct relation of the lifts before they pass to the nailing or fastening mechanism. In the present instance the alining means comprises a series of spring fingers 205, Figs. 3 and 9. These are preferably supported by one of the side guides, as 48, and act upon the heel piles as they are moved past to press yieldingly upon one side of the heel piles and cause them to conform to the incline or surface of the opposite guide 47. The spring fingers separately act upon the heel pile at different points in its height and just prior to delivery of a pile to the nailing mechanism.

It is proposed in the present heel building machine to secure the lifts of each pile in their assembled and alined relation, and to complete the illustration in this respect a suitable heel nailing mechanism is shown, but as its details form no essential part of the present invention it is not herein described. If desired the nailing mechanism may be the same as that shown and described in the prior application hereinbefore mentioned.

What is claimed is:—

1. In a heel building machine, the combination of means for holding a series of stacks of heel lifts, stationary lift supporting means arranged at one side of and below the plane of the bottoms of the stacks of heel lifts, means for simultaneously moving a lift from each stack and delivering the series to the lift supporting means, and means for advancing the line of delivered heel lifts relatively to the supporting means.

2. In a heel building machine, the combination of means for holding a series of stacks of heel lifts, a stationary lift support extending past the several stacks at one side thereof and in a plane below the bottom of the stacks, means for moving a heel lift from each of the stacks and simultaneously delivering the series to the lift support, and heel lift advancing means for simultaneously advancing the series of lifts step-by-step along the support.

3. In a machine of the class described, the combination of a means for holding a series of stacks of heel lifts, stationary heel lift-receiving means extending past the series of

stacks below the plane of their bottoms and normally in fixed relation thereto, a cementing roll to engage the lifts in transit from the stacks to the receiving means, and means for moving a heel lift from each of the stacks and simultaneously delivering the series to the relatively lower lift receiving means.

4. In a machine of the class described, the combination of a means for holding a series of stacks of heel lifts, stationary heel lift-receiving means extending past the series of stacks below the plane of their bottoms, a cementing roll to engage the lifts in transit from the stacks to the receiving means, means for moving a heel lift from each of the stacks and simultaneously delivering the series to the relatively lower lift-receiving means, and means for advancing the series of lifts step-by-step relatively to the receiving means.

5. In a machine of the class described, the combination of a series of magazines for holding a series of stacks of heel lifts, a stationary lift-support at one side of the series of magazines below the plane of their bottoms, a conveyor having a series of devices arranged to engage partially formed heel piles on said support and move them intermittently along the support, and means for removing a heel lift from each of the magazines and simultaneously delivering one lift to each of the partially formed piles.

6. In a machine of the class described, the combination of a series of magazines for holding a series of stacks of heel lifts, a stationary support for supporting a row of heel lifts at one side of and below the plane of the bottoms of the magazines, a conveyor movable intermittently in one direction and provided with devices for advancing heel lifts on said support, and means for moving a lift from each magazine and simultaneously delivering one of the series of lifts to each pile on the support in each of its positions of rest.

7. In a machine of the class described, the combination of a series of magazines for holding a series of stacks of heel lifts, a stationary support for supporting heel lifts below the plane of the bottoms of the magazines, heel lift pasting means between the magazines and support, a conveyor movable intermittently in one direction and provided with devices for advancing heel lifts on said support, and means for moving a lift from each magazine and simultaneously delivering one of the series of lifts to each pile on the support in each of its positions of rest.

8. In a machine of the class described, the combination of a series of magazines for holding a series of stacks of heel lifts, a stationary support for supporting heel lifts in a row at one side of and below the plane

of the bottoms of the magazines, a conveyor 5
movable intermittently in one direction and
provided with devices for advancing heel
lifts on said support, and means for remov-
ing a heel lift from each of a number of
magazines equal to the number of lifts in
a heel and simultaneously delivering one to
each pile on the support in each of its posi-
tions of rest.

16. 9. A heel building machine comprising, in
its construction, a series of heel lift maga-
zines, heel lift edge guiding means extend-
ing past the series of magazines, a lift sup-
porting surface below the plane of the maga-
zine bottoms, means movable intermittently
in one direction for advancing lifts on said
supporting surface, and means for remov-
ing a lift from each of the magazines and
simultaneously delivering one lift to each
20 partially formed pile of lifts on the sup-
porting surface.

10. A heel building machine, comprising,
in combination, a series of heel lift maga-
zines, a guide for heel lifts extending past
25 said series of magazines and having a lift
supporting surface below the plane of the
magazine bottoms and upwardly converg-
ing sides, means for intermittently advanc-
ing heel lifts in said guide from one lift
30 receiving station to another, and means for
removing a series of lifts from the maga-
zines and simultaneously delivering one lift
of the series to the guide at each lift re-
ceiving station during each period of rest
35 of the advancing means.

11. In a heel building machine, the com-
bination of a series of magazines for hold-
ing a series of stacks of heel lifts of vary-
ing dimensions, a support for heel lifts at
40 one side of the magazine and below the
plane of their bottoms, side members con-
verging upwardly from said support, means
for intermittently advancing heel lifts on
said support, and means for removing a
45 series of heel lifts of varying dimensions
from the stacks and simultaneously deliver-
ing a lift of appropriate dimension directly
to each of a series of partially formed heel
piles on the support and between the side
50 members.

12. A heel building machine comprising,
in combination, a series of heel lift maga-
zines, a guide for heel lifts extending past
55 said series of magazines and having a lift
supporting surface below the plane of the
magazine bottoms and upwardly converg-
ing sides, means for intermittently advanc-
ing heel lifts in said guide from one lift re-
ceiving station to another, and a series of
60 yielding members acting on a pile of heel
lifts as they are advanced between the sides
of the guide to align the lifts.

13. A heel building machine comprising,
in combination, a series of heel lift maga-
zines, a guide for heel lifts extending past
65

said series of magazines and having a lift
supporting surface below the plane of the
magazine bottoms and upwardly converg-
ing sides, means for intermittently advanc-
ing heel lifts in said guide from one lift 70
receiving station to another, and a series
of yielding fingers arranged inclined to the
vertical and acting on a pile of heel lifts
as they are advanced to align the lifts.

14. A heel building machine comprising, 75
in combination, a series of heel lift maga-
zines, a guide for heel lifts extending past
said series of magazines and having a lift
supporting surface below the plane of the
magazine bottoms and upwardly converg-
80 ing sides, means for intermittently advanc-
ing heel lifts in said guide from one lift
receiving station to another, and a series of
yielding fingers extending horizontally and
inclined to the vertical and acting on a pile 85
of lifts as they are advanced to align the lifts.

15. In a heel building machine, the com-
bination of a heel lift magazine, lift past-
ing means, a lift support adjacent to the 90
magazine, means for removing a lift from
the magazine and presenting it successively
to the pasting means and lift support, and
means for engaging the edge of a pasted lift
95 for detaching it from the removing means
and insuring its delivery to the lift support.

16. In a heel building machine, the com-
bination of a heel lift magazine, a pasting
device adjacent to the magazine, a pusher
arranged to push a lift from the magazine 100
past the pasting device to a predetermined
position, and means for engaging the trail-
ing edge portion of the pasted lift for pre-
venting adhesion of the lift to the pusher
when the latter is retracted. 105

17. In a heel building machine, the com-
bination of a heel lift magazine, a pasting
device adjacent to the magazine, a pusher
arranged to push a lift from the magazine
past the pasting device to a predetermined 110
position, and a lifter which is raised by
the pasted lift as it is advanced by the
pusher and holds the lift from following the
pusher as the latter is retracted.

18. In a heel building machine, the com-
bination of a heel lift magazine, a lift sup-
port below the plane of the bottom of the
magazine, a pasting device between the
magazine and lift support, a pusher ar-
ranged to push a heel lift from the maga-
zine past the pasting device for delivery to
the lift support, and a stop arranged to be
interposed in the path of movement of the
lift and acting to detach it from the pusher
and insure its delivery to the support as the
pusher is retracted. 125

19. In a heel building machine, the com-
bination of a heel lift feeding pusher, a
paste roll in the path of the heel lift as it 130
is fed by the pusher, and a lifter that is

- raised by the pasted heel lift and that drops behind the lift to detach it from the pusher as the latter is retracted.
20. In a heel building machine, the combination of a heel lift feeding pusher having a recess, a paste roll in the path of the heel lift as it is fed by the pusher, and a stop that is arranged to pass into the recess of the pusher behind the pasted lift to prevent the lift following the pusher as the latter is retracted.
21. In a heel building machine, the combination of a heel lift magazine, a pusher arranged to push a heel lift from the magazine to a predetermined position, a lifter arranged to be raised by the heel lift as it is moved by the pusher and to hold the lift from following the pusher as it is retracted, and means for stopping the machine, if the lifter fails to be raised by a heel lift.
22. In a heel building machine, the combination of a series of magazines for holding stacks of heel lifts, a lift support extending adjacent to the magazines, means for removing a series of lifts from the magazines and delivering them to the support, lifters adapted to be raised by the heel lifts as they are moved by the removing means, and means for stopping the machine should any one of the lifters fail to be raised by a heel lift.
23. In a heel building machine, the combination of means for holding a series of stacks of heel lifts, heel lift assembling means, means for removing a series of heel lifts from the magazines and delivering them to the assembling means, a vibrator, means for stopping the machine upon arrest of the vibrator, and a series of stops normally in the path of movement of the vibrator and removed from said path by the heel lifts.
24. In a heel building machine, the combination of means for holding a series of stacks of heel lifts, heel lift assembling means, means for removing a series of heel lifts from the magazines and delivering them to the assembling means, a vibrator, means for stopping the machine upon arrest of the vibrator, and a series of stops controlled by the heel lifts as they are being presented to the assembling means for stopping the vibrator should one of the series of lifts fail to be presented.
25. In a heel building machine, the combination of a series of magazines for holding stacks of heel lifts, a lift support extending uninterruptedly adjacent the series of magazines, means for moving simultaneously a series of heel lifts from the magazines to the support, and mechanism for stopping the machine upon failure of the lift moving means to deposit a complete row of lifts.
26. In a heel building machine, the combination of an endless chain lift assembling device, power operated means for imparting movement to said device, a yielding connection between said device and said means, and means operated by relative movement of said device and said power operated means, due to the yielding of said connection, for disconnecting the power.
27. In a heel building machine, the combination of an endless chain lift assembling device, power operated means for imparting step by step movement to said device in a straight line, a yielding connection between said device and said means, and means for disconnecting the power, operated by the yielding of said connection upon the assembling device encountering an obstruction.
28. In a heel building machine, the combination of a heel lift support, mechanism for delivering a row of heel lifts to said support, assembling means for moving a row of lifts along said support, and means for stopping the machine upon failure of a complete row of lifts being delivered to the support and upon undue obstruction to the movement of the row along said support.
29. In a heel building machine, the combination of a heel lift magazine, a pasting roll adjacent to the magazine, a pusher arranged to push a lift from the magazine past the pasting roll to a predetermined position, means for stopping the machine if a heel lift fails to be delivered by the pusher, and means for continuously rotating the pasting roll.
30. In a heel building machine, the combination of means for supporting a series of stacks of heel lifts, lift feeding mechanism for simultaneously feeding a series of lifts from the stacks to a predetermined position, a pasting roll located in the paths of the lifts as they are fed by the feeding mechanism, independently mounted scrapers acting upon the paste roll adjacent the path of the lifts, and means for independently adjusting the scrapers relatively to the roll for varying the amount of paste that may be delivered to different lifts.
31. In a machine of the class described, the combination of heel lift feeding mechanism, and a magazine that is constructed to hold a stack of wedge-shaped lifts of indeterminate height and has its delivery portion shaped to shift the lifts rearwardly of superposed lifts in the direction of their thicker edges as the lifts approach delivery position.
32. In a machine for feeding wedge shaped articles, the combination of means for maintaining and guiding the articles in stacked relation with their thick edges held in engagement with each other by gravity and their thin edges separated and lower than the

respective thick edges, and means for removing articles, one at a time, from the end of the stack.

33. In a machine of the class described, the combination of heel lift feeding mechanism, a magazine that is constructed to hold a stack of wedge-shaped heel lifts, a support for the lowermost lift of the stack, means for causing the weight of superposed lifts 65 to act upon the lowermost lift forward of the rear edge thereof and hold it flat on the support, and means for preventing relative swinging movement of the lifts about vertical axes as they move towards delivery 70 position.

34. In a machine of the class described, the combination of heel lift feeding mechanism, and a magazine for holding a stack of wedge-shaped heel lifts having its delivery portion provided with inclines so disposed as to cause the lowermost lift to move rearwardly relative to the breast edges of superposed lifts as it approaches delivery 80 position.

35. In a machine of the class described, the combination of heel lift feeding mechanism, a magazine for holding a stack of wedge-shaped heel lifts having its delivery portion provided with inclines so disposed as to cause the lowermost lift to move rearwardly relative to the breast edges of superposed lifts as it approaches delivery position, and means for maintaining the breast edges of the lift contours in parallel relation 90 as the lifts move towards delivery position.

36. In a heel machine, the combination of feeding mechanism for feeding heel lifts, a magazine for holding a stack of heel lifts and comprising a breast guide, and a rod 95 on which the heel lifts are strung, the breast guide and rod adjacent the delivery end of the magazine being inclined rearwardly of the heel lifts.

37. In a heel building machine, the combination of means for holding a series of stacks of heel lifts, stationary lift supporting means arranged at one side of and below the plane of the bottoms of the stacks of heel lifts and normally in fixed relation 100 thereto, and means for simultaneously moving a lift from each stack and delivering the series to the lift supporting means.

38. In a heel building machine, the combination of means for holding a series of stacks of heel lifts, a lift support arranged below the plane of the bottom of the stacks of heel lifts, means for simultaneously removing a number of lifts equal to the total number to be contained in a complete heel 105 pile from the stacks and delivering them to the lift support, a lift assembling means

for advancing the entire series of lifts along the support step-by-step, and means for actuating the lift removing means to deliver a series of lifts after each step movement 65 of the assembling means.

39. In a heel building machine, the combination of a rod on which a stack of heel lifts are strung and having an inclined end delivery portion to direct the heel lifts rearwardly as they pass to feeding position, and means for supporting the rod in position to deliver the heel lifts. 70

40. In a heel building machine, a magazine for holding wedge-shaped heel lifts, comprising, in combination, a heel lift breast guide along which the breast of the heel lifts travel as they move towards delivery position, and a rod passed through the wedge-shaped lifts and having an inclined portion to direct the lifts in a direction rearwardly as they pass to delivery position. 75

41. In a heel building machine, a magazine for holding wedge-shaped heel lifts, comprising, in combination, a heel lift breast guide along which the breast of the heel lifts travel as they move towards delivery position, a rod passed through the wedge-shaped lifts and having an inclined portion to direct the lifts in a direction rearwardly as they pass to delivery position, and means for detachably supporting the rod. 80

42. In a heel machine, the combination of a rod on which a stack of wedge-shaped heel lifts are strung, and having an inclined end 95 portion for deflecting the lowermost lift rearwardly as it passes to delivery position, and heel lift feeding means for removing the lowermost lift from the stack.

43. In a heel machine, the combination of a rod of non-circular cross-section on which a stack of wedge-shaped heel lifts are strung, and having an inclined end portion for deflecting the lowermost lift rearwardly as it passes to delivery position, and heel lift 100 feeding means for removing the lowermost lift from the stack. 105

44. In a heel machine, the combination of a rod on which a stack of wedge-shaped heel lifts are strung and having an inclined 110 delivery end portion for deflecting the lowermost heel lift rearwardly as it passes to delivery position, heel lift feeding means for removing the lowermost lift of the stack and feeding it to a predetermined position, and means for holding the heel lift from turning in a plane passed through the surface of the heel lift. 115

In testimony whereof I have signed my name to this specification.

RALPH C. SIMMONS.
